UNITED STATES PATENT OFFICE.

ALBERT MALSIN, OF NEW YORK, N. Y.

BRASSIÈRE.

1,145,204.

Specification of Letters Patent. Patented July 6, 1915.

Application filed July 13, 1914. Serial No. 850,617.

To all whom it may concern:

Be it known that I, ALBERT MALSIN, citizen of the United States of America, residing at New York, in the county of New York and State of New York, have invented certain new and useful Improvements in Brassières, of which the following is a specification.

The present invention relates to an adjustable brassière or bust supporter for use during pregnancy and has for its object to make the same of a construction that at all times will hold the busts tightly in position and prevent them from hanging down or becoming flabby.

The prevailing method now is to provide the brassière with lacings or elastics at its sides or elastics at the bottom of the brassière. Such method, however, has proved to be objectionable because as the wearer's figure enlarges the material not only at the sides or bottom, but also around the busts, stretches, thereby loosening the latter and thus defeating the object of the brassière. To overcome this objection my new brassière has triangular or dart like incisions, the pointed ends of which are located below the lowest part of the busts and in which are inserted and fastened correspondingly cut pieces of material of sufficiently large width so as to give all the required fullness when the brassière stretches by reason of the enlargement of the wearer's figure. The base of the dart shaped material is Shirred and elastic. Owing to this structure the pointed ends of the triangular pieces will act as pivotal points around which the former will swing while stretching as the figure enlarges, whereas that part of the material of the brassière which envelops the busts will at all times remain perfectly tight and hold the busts in the required position.

My invention also relates to other improvements which will be hereinafter fully described and set forth in the annexed claims.

To make my invention more clear, the same is illustrated in the accompanying drawing in which similar reference characters denote corresponding parts and in which—

Figure 1 is a rear view of an unfolded brassière constructed in accordance with my invention and Fig. 2 shows the brassière in use.

Referring specifically to the drawing

which forms part of this specification, *a* denotes the brassière which below the lowest part of the bust is provided with triangular or dart like incisions in each of which is inserted and fastened by stitching a correspondingly cut piece of material *b* of sufficiently large width, so as to give the required fullness when the brassière stretches in the measure as the wearer's body enlarges. The pointed ends *b'* of said darts are located below the lowest part of the busts or the bust line *a'*. These inserted pieces of material *b* may be stiffened at their edges by whalebone or steel, as at *d*. The lower ends of the inserted pieces *b* are folded upon themselves and stitched so as to form a tubing or pocket *b*² for the passage of an elastic band or cord *c*, the ends of which are stitched to the material of the brassière. The elastic band or cord for each part *b* is shorter than the base of the triangular piece *b*, so that normally, that is when the brassière is not stretched, the base of the triangular piece will be Shirred and the material be creased or puckered as at *c'* in Fig. 1. When the brassière is applied to the enlarged figure, the lower part of the brassière containing the pieces *b*, *b* will stretch, the sides of said pieces *b*, *b* swinging around the pivotal points formed at the pointed ends *b'* thereof. The upper part of the brassière, that is the part lying above the line *a'* and enveloping the busts will not stretch and the position of the busts, therefore, will not be affected by the stretching of the lower part of the brassière.

The part of the brassière located above the lowest part of the busts will not change during the enlargement of the figure, but will permanently maintain its size and consequently this part can be cut to fit various sizes. Furthermore, to give the necessary freedom of movement, the brassière is provided at its shoulders with elastic bands *e*.

My new brassière may be provided with short sleeves *f* to enable the wearer to insert shields.

Although I have shown the brassière provided with two adjustable pieces, it is understood, that only one may be used. There also may be other changes made in the construction without departing from the spirit of my invention. I therefore do not wish to restrict myself to the details shown and described.

What I claim is:

1. A brassière, having in front triangular

or dart-like incisions, the bases of which extend in line with the lower edge of the brassière and the apexes of which lie immediately below the lowest bust line, stiffening means along the edges of said incisions, pieces of material of similar shape but of greater width than the said incisions inserted in the latter and fastened to the edges thereof and elastic members connected to 10 said pieces of material and fixed at their ends to the body of the brassière in contracted state.

2. A brassière, having in front dart-like or triangular incisions, the bases of which are in line with the lower edge of the brassière and the apexes of which lie immedi- 15

ately below the lowest bust line, stiffening means along the edges of said incisions, pieces of material of similar shape but of greater width than the said incisions inserted in the latter and stitched to the edges thereof, the lower edges of said pieces being folded upon themselves to form pockets and elastic members passed through said pockets and fastened at their ends to the body of the 25 brassière in contracted state.

In testimony whereof I affix my signature in presence of two witnesses.

ALBERT MALSIN.
